TOGGERY RACK

Samuel C. Awbrey, Kansas City, Mo.

Application September 23, 1935, Serial No. 41,683

3 Claims. (Cl. 211—120)

This invention relates to supporting devices for wearing apparel such as hats, ties, trousers and similar garments, and has for its primary object, the provision of a toggery rack, wherein 5 is combined unique, durable and effective means for holding such articles for convenient placement and removal. One of the important aims of the instant invention is to provide in a toggery rack, means for holding trousers, which comprises a strip of resilient material rebent upon itself a recurring number of times to present a series of open-end slots, which open ends are formed in a novel manner to present at least one guide wall adjacent the entrance to the respective slots so that a garment may be moved to the gripped position without difficulty.

An even further object of this invention is to provide a toggery rack of the aforementioned character, wherein is incorporated a hat holder which overhangs the pants holder and a tie rack, which is affixed to the outermost length of the rebent strip of resilient material, all to the end that interference between the toggery held by the rack is obviated and any or all of the articles 20 which the rack is designed to support may be moved to and from the supported position with ease.

In addition to the foregoing broader objects of this invention, the following specification will 30 disclose minor objects that contribute in the production of a most desirable article of manufacture.

In the drawing:

Figure 1 is a perspective view of a toggery rack 35 made in accordance with this invention.

Fig. 2 is an end elevation of the same.

Fig. 3 is a longitudinal, cross section through the rack, taken along line III—III of Fig. 1, and,

Fig. 4 is a perspective view of a toggery rack 40 embodying a modified form of the invention.

The toggery rack comprises a strip of resilient material 6, rebent upon itself a recurring number of times to present a plurality of open-end slots 8, within which is positioned a garment such as 45 a pair of trousers or the like. Strip 6 is flat and bent so that when the weight of the garments is thereupon, it will not sag. The inherent resiliency of strip 6 is such that the garments moved into slots 8 are securely held and to facilitate insertion, the bights 10 formed by rebending, are disposed in offset relation so that a guide wall 12 50 is presented adjacent the mouth of each slot respectively.

As illustrated in Fig. 3, bights 10 are on a line 55 extending at an angle transversely across the

body portion of the rack and in order to complete the provision of a guide wall at each slot respectively, the outermost length 14 of the rebent strip 6 is extended as at 16 so that the guide wall 18 is formed thereon. This outermost length 5 14 has means formed thereby, whereby the rack in its entirety may be secured to a supporting surface. In the illustrated embodiment of the invention seen in Figs 1, 2 and 3, the offset portions 20 of this outermost length 14 afford convenient 10 structure for securing the rack in position. There is an opening 22 formed in offset portions 20 and a screw 24 is passed through this opening 22 into the support.

A hat holder comprising a pair of uprights 26 15 and an intermediate bow 27, is associated with the rebent strip in the manner shown. The uprights 26 overlie offset portions 20 and an opening 28 formed therein on each side respectively of offset 20 receives a screw 30 to further fasten 20 the rack in place. Uprights 26 having laterally projected portions, insures that bow 27 and the remaining portions of uprights 26 are in an overhanging relation with respect to strip 6, before described. The hat holder in the form of uprights 26 and bow 27 is preferably formed of 25 flat strip stock which is rigid, yet light. The manner of forming uprights 26 to embrace offsets 20 should be followed and the height of uprights 26 may be varied to suit conditions so long as the 30 width of the hat brim is taken into consideration.

The tie rack 32 which is secured along the other outermost length 34 of strip 6 is provided with outwardly extended angular wings 36 that 35 serve as guide walls in that they have the ends thereof terminating in substantially the same transverse plane as the ends of outermost length 14. With this construction, there is formed at each end of the rack, a small bay-like indentation, bottomed by the entrance to the several slots 8. This feature of the rack is valuable in that 40 garments may be moved into the slots 8 through the guidance of the several walls mentioned and because of the projecting wings 36 just mentioned.

Each of these wings has a notch 38 formed therein for the purpose of receiving any article that may be hung thereon and ties are looped over the several fingers 40 forming a part of tie rack 50 32. The back strip 42 of tie rack 32 is secured directly to the outermost length 44 of strip 6 and when garments are moved to position in slots 8, the expansion and contraction of the rebent strip 6 moves tie rack 32 toward and from the support 55

so that interference with the garments held within these said slots does not take place.

In the form of the invention illustrated in Fig. 4, strip 50 is bent in the same fashion as before described and a tie rack 52 is secured to the outermost length of said strip 50, as before mentioned. The only variation between the toggerack illustrated in Figs. 1 to 3 inclusive over that illustrated in Fig. 4 is the specific manner of creating offset 54, which has openings 56 therethrough to receive suitable fastening elements to hang the rack upon a support.

Also, in this form, the hat rack does not form a part of the completed structure.

15 Having thus described the invention, what is claimed as new and desired to be secured by Letters Patent is:

1. A toggerack comprising a strip of resilient material rebent upon itself a recurring number of times to present open-end slots, the bights and ends of said strip being in longitudinal offset relation; and a strip of material secured to one of the outermost lengths of said strip material in overlapped relation whereby a guide wall 20 is presented at the entrance to each adjacent slot respectively.

2. A toggerack comprising a strip of resilient material rebent upon itself a recurring number of times to present open-end slots, successive lengths of said strip being progressively shorter as one outermost length thereof is approached from the other outermost length; and an outwardly and forwardly extending wing at each end respectively of the shortest outermost length of material whereby a guide wall is presented at the entrance to each adjacent slot respectively. 5

10 3. A toggerack comprising a strip of resilient material rebent upon itself a recurring number of times to present open-end slots, successive lengths of said strip being progressively shorter as one outermost length thereof is approached from the other outermost length; and a wing at each end respectively of the shortest outermost length of strip material and extending therebeyond whereby a guide wall is presented at 15 the entrance to each slot respectively, each wing being angled forwardly so that the free end thereof extends outwardly from said shortest length of strip material. 20
